UNITED STATES PATENT OFFICE

GIDEON SUNDBACK, OF MEADVILLE, PENNSYLVANIA, ASSIGNOR TO HOOKLESS FASTENER COMPANY, OF MEADVILLE, PENNSYLVANIA, A CORPORATION OF PENNSYLVANIA

SEPARABLE FASTENER

Original application filed February 11, 1925, Serial No. 8,340. Divided and this application filed March 31, 1928. Serial No. 266,362.

This invention relates to separable fasteners of the slider controlled type and is a division of my copending application Serial No. 8,340, filed February 11, 1925.

5 An object of the invention is to provide a separable fastener which has increased lateral flexibility together with the ability to compensate for a variation in the length of the fabric stringers to which the interlocking 10 means are attached, yet is secure, strong, and capable of being made cheaply in large quantities.

Another object of the invention is to provide a novel construction of oppositely interlocking members having increased factors of strength, security, flexibility and ease in locking and unlocking.

The fastener shown in my Patent 1,219,881, dated March 20, 1917, embodies continuous 20 fabric stringers carrying locking members alike on each stringer, but in alternating or staggered arrangement, whereby interlocking is effected by the engagement of each member on one stringer with two members on the 25 other stringer. As specially worked out in that patent, such fastener has a very considerable lateral flexibility, but little or no accommodation to variation in stringer length owing to the close alternating engagement of 30 the several locking members. It is known that continuous fabric stringers fluctuate considerably in length owing to humidity conditions, a stringer when wet being appreciably longer than when dry. Hence, longitudinal 35 contraction when drying causes the alternately interlocked stringers to wave or curl up out of the interlocking plane, which, while not impairing the security of the fastener, is objectionable in appearance on various articles, particularly on rubber footwear which 40 is subjected to extremes of moisture conditions. This tendency to wave or curl is especially noticeable in footwear because the fastener is usually closed under strain in view 45 of the desirability of securing a good fit, so that the only way the contracting of the stringers can be accommodated is by displacement of the locking members out of the interlocking plane.

50 In the present invention, I have provided

a novel construction of cooperating locking members arranged directly opposite one another along a pair of flexible fabric stringers, with any desired spacing between the members along each stringer. One of each pair 55 of cooperating locking members is provided with a projection and the other with a recess so constructed that they will engage and disengage even though they are somewhat out of alignment due to shrinkage or expansion 60 of the stringers. There is also sufficient flexibility between the interlocked members to compensate for shrinkage or expansion of the stringers thereby reducing the tendency to wave or curl which has heretofore proved 65 objectionable. To facilitate engagement of the projection of one locking member with the recess of another, guiding surfaces are preferably provided longitudinally and transversely of the tip of the projection. 70

According to a specific feature of the invention, one member of each interlocking pair has a pin or lip, and the other member of the pair a cooperating socket. The pin is substantially straight, and projects longitudinally of the stringer with at least the surface of the pin adjacent the edge of its stringer parallel to such edge. The cooperating sockets have walls which are parallel 75 to the edge of the stringer. When a pin of one locking member is seated in the socket of its cooperating locking member, and a transverse force is applied to the stringers in an attempt to separate them, there will be no 80 resulting component of force tending to move the pins longitudinally out of the sockets by reason of the parallel engagement of socket walls and pin surfaces. The cooperating locking members will thus remain securely 85 locked together and can only be separated 90 by the progressive movement of the slider.

In the accompanying drawing:

Fig. 1 is a plan view of a separable fastener embodying the invention;

Fig. 2 is an enlarged section taken on the line 2a—2a of Fig. 1;

Fig. 3 is an enlarged end view of one of the projection members shown in Fig. 1;

Fig. 4 is a plan view of the member shown 100

in Fig. 3, showing the socket in such member;

Fig. 5 is a side view of the member shown in Figs. 3 and 4;

5 Fig. 6 is a plan view showing a section of a fastener having the same type of locking members as shown in Fig. 1 except that they are arranged alternately on the stringers;

10 Fig. 7 is an enlarged perspective view of the recess member shown in Fig. 1 clamped to the corded edge of the stringer; and showing the pin or lip therein;

15 Fig. 8 is an enlarged transverse section through the recess and projection members when interlocked, showing the pin or lip of one member seated in the socket of the other;

20 Fig. 9 is an enlarged perspective view of a modified form of sheet metal locking member; and

Fig. 10 is an enlarged perspective view of still another form of sheet metal locking member.

25 In Fig. 1, the flexible stringers 1 are provided with cords 2 secured along their longitudinal edges. The projection locking members 3 are clamped to the corded edge of one stringer, and the cooperating recessed locking members 4 are clamped to the corded 30 edge of the opposite stringer. These locking members are disposed substantially opposite one another on said stringers and are arranged to be engaged and disengaged by the up and down movement of a slider 5 having diverging channels. The slider may be 35 moved up and down along the stringers by means of a pivoted pull member 6.

40 The upper ends of the two stringers are provided with stop members 7 which are clamped to the corded edges of the stringers and which are large enough to wedge laterally within the slider against each other or against the slider channels to limit the movement of the slider. A bottom stop member 8 is shown clamped to the corded edges 45 at the lower ends of the stringers to fasten the lower ends together and prevent the slider from coming off the fastener when it reaches the lower limit of its travel.

50 The projection locking members 3, shown in detail in Figs. 3, 4 and 5, are stamped out of round material which is bent back on itself at 9 and bent together along the line 10. The free outer ends are spread at 11 to form 55 clamping jaws for engaging the corded edge of the stringer. One side of the bend or fold is stamped to provide a socket 12 and an outer catch or hook portion 13. The socket 12 is adapted to be seated in the pin 60 or lip 14 of the cooperating recessed member 4 with the hook portion 13 engaging the rear side of the pin 14 in the manner shown in Figs. 2 and 8. The walls of the socket 12 are substantially straight, with the wall adjacent the hook portion 13 parallel to the

edge of the stringer to which the member 3 is clamped.

The recessed locking members 4, shown in detail in Fig. 7 are provided with clamping jaws 15 for clamping same to the corded edge of the stringer. The forward end of each member 4 is bent to provide a tube-like portion 16 which is open ended to provide an edgewise recess 17. One wall of the recess 17 is rounded while the opposite wall is substantially flat, as shown in Figs. 2 and 7. The straight pin or lip 14 projects into the recess 17 from the flat wall thereof and extends toward the rounded wall in a plane substantially parallel to the edge of the stringer, as shown in Fig. 7. The free end of the pin or lip 14 is substantially flat to cooperate with the flat wall of the socket 12.

25 The projection members 3, which are formed of rounded stock, are each provided with guiding surfaces 18 and 19 above and below the tip of the projection, and also laterally or transversely thereof, so that said projection member has guiding surfaces to facilitate its cooperation with the recessed member 4 when the projection is slightly out of line with the recess in any direction due to shrinkage or expansion of the stringers. In

30 Fig. 6 the same type of locking members are shown, but the projection and recessed members are alternately arranged on each stringer instead of all members being alike on one stringer as in Fig. 1. When the slider 5 is

35 moved to engage the opposite locking members the guiding surface 19 of each projection member rides over the pin 14 of its cooperating recessed member until the socket 12 engages said pin 14 as shown in Figs. 2 and 8.

40 The engagement between the socket 12 and the pin 14 prevents the locking members from separating under transverse strain when engaged. Since the side of the pin 14 is parallel to the edges of the stringers, and engages the wall of the socket 12 which is also

45 parallel to the edges of the stringers, a transverse force perpendicular to the edges of the stringers will not cause them to move away from each other in a longitudinal direction

50 and hence the members will not come apart accidentally when locked.

55 The open-sided locking member shown in Fig. 9 consists of a strip of sheet metal bent to provide substantially parallel faces 20 connected by a bridging portion 21. A slot 22

60 is cut in the bridging portion 21 to provide compressible jaws for clamping the member to the corded edge of a stringer. The pin or lip 23 is struck up at the free end of one of

65 the faces 20 to receive and retain the socket 12 of an opposite projection member 3. The side of the pin 23 which is adjacent the corded edge of the stringer is parallel to such edge.

70 The opposite free end 24 is rounded, as in Figs. 2 and 7, and limits the upward move-

ment of a cooperating projection member 3 therein, so that the cooperating recessed member and projection member will not come apart when locked except when they are separated at an angle by the diverging channels of the slider.

Fig. 10 shows another form of sheet metal locking member having spaced pairs of clamping jaws 25 joined by the bridging portion 26 in which is stamped the recess 27 for receiving a projection member such as that shown in Fig. 1, the lip 28 being stamped out from the material cut in forming the recess 27. The pin or lip 28 engages the socket of the cooperating projection member in the manner described above.

Among the advantages of this invention may be mentioned increased flexibility of the fastener both laterally and longitudinally. Since the locking members are located opposite each other they may be spaced apart a sufficient distance to give the fastener great lateral flexibility without causing the members to become unfastened. This spacing of the pairs of oppositely disposed locking members also permits contraction and expansion of the stringer material such as occurs when the fastener is used on washable goods, for example, which get wet and shrink on drying. When used on a shoe, for example, the longitudinal spacing of the pairs of cooperating locking members enables the fastener to come and go with the natural movement of the foot in walking without causing the fastener to buckle or feel unduly stiff. The provision of cooperating pins and sockets with surfaces parallel to the edges of the stringers prevents the members from coming apart under strain when interlocked. The provision of guiding surfaces longitudinally and transversely of the tip of each projection facilitates entry of the projections within the recesses of the opposite locking members.

I claim:

1. A separable fastener comprising a pair of stringers having a plurality of pairs of locking members clamped substantially opposite one another thereon, one member of each pair having a recess and a pin projecting into said recess, and the other member of each pair having a socket adapted to enter said recess and engage said pin.

2. A separable fastener comprising a pair of stringers having a plurality of pairs of cooperating locking members clamped substantially opposite one another thereon, one member of each pair having a rounded projection and the other member of each pair having a rounded wall and an opposite flat wall to receive said projection between them, and a portion on said flat wall extending toward said rounded wall to engage said projection.

3. A separable fastener comprising a pair of stringers, a plurality of pairs of cooperat-

ing locking members clamped substantially opposite one another on the adjacent edges of said stringers, one member of each pair having a recess in a plane substantially perpendicular to the edge of its stringer and a pin projecting into said recess substantially parallel to the edge of said stringer, and the other member of each pair having a socket adapted to enter said recess and engage said pin.

4. A separable fastener comprising a pair of stringers, a plurality of pairs of cooperating locking members clamped substantially opposite one another on the adjacent edges of said stringers, one member of each pair having a projection extending straight out from one stringer and the other member of each pair having a tubular portion extending straight out from the other stringer and at right angles to the edge of said stringer to receive said projection.

5. A separable fastener comprising a pair of stringers, a plurality of pairs of cooperating locking members clamped substantially opposite one another on the adjacent edges of said stringers, one member of each pair having a hooked projection extending straight out from one stringer and the other member of each pair having a tubular portion extending straight out from the other stringer and at right angles to the edge of said stringer to receive said projection, and a lip projecting into said tubular portion to engage the hooked portion of said projection to prevent said locking members from separating under transverse strain when engaged.

6. A separable fastener comprising a pair of stringers, a plurality of pairs of cooperating locking members clamped substantially opposite one another on the adjacent edges of said stringers, one member of each pair having a rounded projection and a hook portion set in from the end of said projection, and the other member of each pair having a rounded wall and an opposite flat wall to receive said projection between them, and a lip on said flat wall substantially parallel to the edge of the stringer to engage the hook portion of said projection.

7. A locking member for a slide type fastener comprising a strip of material bent upon itself and having clamping jaws formed in each of the ends of said material, a part of the bent portion of said member being punched out to form an irregular recess with a projection extending into said recess to engage a cooperating locking member.

8. A locking member for a slide type fastener comprising a strip of material bent upon itself to provide a bridging element, means for clamping said member to a stringer, and a recess in said bridging element having one edge rounded and the opposite edge provided with a lip extending toward said rounded edge.

9. A locking member for a slide type fastener comprising a flat strip of material bent upon itself in the middle and having outwardly extending ends adapted to receive a projection of a cooperating locking member between them, a lip on one end of said member projecting toward the other end thereof to engage and retain the projection of the cooperating locking member therein, and compressible clamping jaws formed in said member at the bend.

10. A locking member for a slide type fastener comprising a flat strip of material bent upon itself in the middle and having end portions one of which is rounded to facilitate entry of the projection of a cooperating locking member and the other of which is provided with a projecting lip to retain such projection between said ends, and compressible clamping jaws formed in said member at the end.

11. A separable fastener comprising a pair of flexible stringers, a series of spaced locking members carried by each stringer, each of said locking members being fixedly attached at one end to its stringer, the free ends of the members of one series being adapted to enter the members of the other series, certain of said members having sockets with flat walls and the members cooperating therewith each having a pin with its free end substantially flat for engagement with a wall of a socket.

12. A fastener of the class described comprising a pair of flexible stringers, a series of fastener elements mounted on each stringer, each element of each series being rigidly attached at one end to its respective stringer, the free ends of said elements being adapted to overlap, each element of one series having a socket provided with a wall disposed parallel to the edge of the stringer, and a pin projecting from each fastener element of the other series, said pins being adapted to enter the sockets in the elements of the first series, each pin having a surface parallel to the edge of the stringer adapted to engage the aforesaid wall of the corresponding socket whereby positively to resist separation of said elements.

13. A fastener of the class described comprising a pair of stringers each carrying a series of spaced fastener elements, an element of one series cooperating with an element of the opposed series to form an interlocking pair, each element of each series being provided at one end with means for rigidly attaching it to the edge of its stringer, the other or free ends of the elements of such an interlocking pair normally overlapping, the free end of one element of such pair being provided with a socket, and a pin projecting from the free end of the other element of said pair, said pin normally fitting within the socket of the other element, the opposed

surfaces of the engaging pin and socket being so shaped that separating stress applied in a direction perpendicular to the edges of the stringers is devoid of any component tending to withdraw the pin endwise from its socket.

14. A fastener of the class described, comprising opposed series of spaced fastener elements, the elements of the respective series each being rigidly attached at one end thereof to flexible stringers, the other ends of said elements projecting free from the stringer edge substantially in lateral alignment with said attaching ends and certain of said elements having sockets in their free ends each provided with a substantially straight wall and others of said elements having pins on their free ends engageable with said sockets, that surface of each pin adjacent to the edge of the stringer being substantially straight and parallel to said edge.
